UNITED STATES PATENT OFFICE.

JOHN J. JONES, OF ELLWOOD CITY, PENNSYLVANIA.

CONTINUOUS SHEET AND TIN-PLATE FURNACE.

Application filed October 18, 1924. Serial No. 744,450.

To all whom it may concern:

Be it known that I, JOHN J. JONES, a citizen of the United States, residing at Ellwood City, in the county of Lawrence and State of Pennsylvania, have invented new and useful Improvements in Continuous Sheet and Tin-Plate Furnaces, of which the following is a specification.

This invention relates to furnaces for the treatment of steel and other metals during rolling thereof, and more particularly to what I term a continuous sheet and tin plate furnace.

One of the main objects of the invention is to provide a furnace of simple and efficient construction and operation which will act to heat the packs of plates or sheets after they have been passed through the rolls and doubler, the operation of the furnace being continuous so as to eliminate any delay or lost motion in the rolling operation. A further object is to provide a furnace of this character which will quickly heat the packs during travel of the same through the furnace, the packs being heated uniformly throughout so as to facilitate the rolling operation and produce sheets of uniform gauge and grade eliminating waste due to improper rolling of the sheets. A further object is to provide a furnace which, after one run is completed, can be used to heat billets to be rolled for a succeeding run, thus ensuring continuous operation of the rolls. Further objects will appear from the detail description.

In the drawings:

Fig. 1 is a top plan view of the furnace;

Fig. 2 is a side view of the furnace;

Fig. 3 is a section taken substantially on line 3-3 of Fig. 1;

Fig. 4 is a section taken substantially on line 4-4 of Fig. 5;

Fig. 5 is a section taken substantially on line 5-5 of Fig. 4;

Fig. 6 is a section taken substantially on line 6-6 of Fig. 5;

Fig. 7 is a section taken substantially on line 7-7 of Fig. 4;

Fig. 8 is a front view of one of the trays and associated parts of the furnace conveyor;

Fig. 9 is a side view of one of the trays and associated parts of the furnace conveyor;

Fig. 10 is a fragmentary horizontal section of a modified form of furnace;

Fig. 11 is a plan view of the rear portion of the furnace showing the billet conveyor or chute in position;

Fig. 12 is a side view of the billet conveyor;

Fig. 13 is a top plan view of the front portion of the furnace showing the means for controlling the operation of the return conveyor;

Fig. 14 is a side view of the front portion of the furnace partly broken away;

Fig. 15 is a plan view of one of the conveyor trays.

In constructing the furnace I provide an elongated casing 1 of approximately rectangular cross-section, this casing being constructed of any suitable refractory material. Top wall 2 of casing 1 is inclined upwardly and inwardly of the casing and a stack 3 communicates with the interior of the furnace at the upper end of wall 2, a baffle 4 depending from the rearward end of top wall 2 so as to cause the products of combustion from the fire chambers to pass into the stack. The rearward end of casing 2 is closed by a hood 5 provided with an opening 6, normally closed by a swinging door 6^a, through which the packs are discharged onto an inclined chute 7 of slatted construction which discharges onto a stand or table 8 from which the packs are removed by an operator and passed into the rolls. The chute and stand are well known in this art and need not be illustrated and described in detail.

The forward end of casing 1 is closed by a hood 9, normally closed by a swinging door 9^b, in which is rockably mounted a shaft 10 on which is secured a receiving fork 11 which includes an upper member 12 and a lower member 13 which are disposed in spaced parallel relation and are rigidly secured together, the lower member being composed of a plurality of parallel bars which are spaced apart to receive between them upwardly projecting fingers 14 of carrier trays 15 which are also of gratalelike construction, each tray consisting of a plurality of parallel bars connected by a base 16. Each tray is provided with a depending stem 17 having adjacent its lower end a transverse arm 18 on each end of which is rotatably mounted an anti-friction roller 19. The lower end of stem 17 is secured to a sprocket chain 20 which passes about sprocket wheels 21 secured on shafts 22 and 22^a rotatably mounted in the furnace adja-

cent the ends thereof, shaft 22 being extended through one side of the furnace and being driven at a predetermined speed by a motor (not shown) or in any other suitable or preferred manner. Arms 18 of stems 17 of the trays operate in channel 23 provided in a guide plate 24 of refractory material secured in casing 1 and positioned beneath flanges 25 which project inwardly from the side walls of the casing, the inner edges of these flanges being spaced apart and plate 24 being provided with vertically extending slots which accommodate stems 17 of the carriage. This provides simple and efficient means for supporting the upper run of the conveyor and this supporting means serves to divide the interior of casing 1 into an upper compartment 26 and a lower compartment 27^a which extends substantially the full length of the interior of the casing and are in communication with each other. As will be noted more clearly from Fig. 5, flanges 25 and plate 24 are disposed at an upward inclination toward the rear of the casing being approximately parallel with top wall 2. The lower run of the conveyor is supported by angle guide strips 27 disposed to receive rollers 19, these strips being supported on brackets 28 secured to the side walls of casing 1. The top wall 9^a of hood 9 is inclined downwardly and forwardly of the furnace and an inclined receiving apron 29 is mounted on the rearward end of top wall 2 and disposed in substantial parallelism with portion 9^a of hood 9. The receiving fork is normally held in receiving position with the bars of lower member 13 in alignment with apron 29 by means of a counter weight 30 secured on an arm 31 which is secured to bar 10. The packs of plates, as they are discharged from the doubler, are placed on a stand or table 32 of known construction by an operator from which they are removed by a return conveyor 33 of known construction from which the packs are discharged onto the receiving apron 29 and thence into the receiving fork. The weight of the packs tilts the receiving fork downwardly so as to bring member 13 thereof into substantial parallelism with the adjacent tray of the conveyor and, during travel of the conveyor, fingers 14 contact with the pack and remove it from the fork which is returned to receiving position by counter weight 30. The bars of chute 7 project through opening 6 into the furnace and are so positioned as to engage between the bars of the conveyor tray so as to remove therefrom the pack as the tray reaches the end of its travel toward the rear of the furnace, the pack sliding down the chute 7 onto table 8 from which it is removed and placed in the rolls by an operator. The tray then travels forwardly of the furnace until it reaches the receiving fork from which it

removes another pack of sheets and conveys the same to the rear of the furnace in the manner described. As the construction and operation of the table 32 and the return conveyor 33 are well known in this art it is not thought necessary to illustrate or describe the same in detail.

For heating the furnace I provide two fire chambers 34 at opposite sides of and adjacent the front of casing 1. Each of these chambers includes a grate 35 of known construction above which is a combustion chamber 36, an ash pit 37 being provided beneath the grate, suitable doors 38 being provided to give access to the combustion chamber and the ash pit. The combustion chambers 36 of the fire chambers 34 have direct communication with upper compartment 26 of the interior of the casing by means of suitable openings 39 provided through the side walls of casing 1 for that purpose. The products of combustion flow directly from the fire chambers into compartment 26 and through this compartment to the stack 3. To prevent the products of combustion from escaping from the front of the furnace through hood 9 I provide a baffle 4^a which depends from the forward end of top wall 2. In this way the packs carried by the trays of the conveyor are subjected to high temperature during travel thereof through the furnace so as to be uniformly heated to the proper temperature for rolling before being discharged from these trays onto the table 8. This provides a furnace of continuous operation in which the packs are heated uniformly and any material loss of heat is eliminated since the furnace is closed at both ends and the greater portion of the products of combustion are caused to flow through the upper compartment of the furnace casing. After the furnace has been in operation for a short time the whole interior thereof is raised to a high temperature so that the trays of the conveyor traveling on the lower run thereof do not cool to any appreciable extent thus conserving time and avoiding sudden cooling of the packs, which ensures uniform heating and temper of the packs thus facilitating rolling thereof and avoiding waste. As the end of a run is approached, billets to be rolled are fed onto the receiving fork 11, these billets being deposited by the fork onto the trays of the conveyor. They are heated to a sufficiently high temperature for the preliminary rolling, being returned to the furnace from the folder by means of the return conveyor in the form of packs in the manner previously described. When passing the billets through the furnace for heating the same the speed of operation of the conveyor may be cut down or reduced so as to ensure thorough heating of the billets to the proper temperature, if de-

sired, though this is not ordinarily necessary as the interior of the furnace will be heated to a high temperature by the heat when the end of the first run is reached so that the 5 billets which travel through the furnace after the first run will be heated to proper rolling temperature in a comparatively short time.

As the billets are usually run through a 10 different set of rolls than the packs at the beginning of the rolling operation I preferably provide a suitable chute such as that illustrated in Figs. 11 and 12 for receiving the billets from the furnace and directing 15 them to a suitable position to be fed to the first rolls. This chute includes an elongated U-shaped frame 40 in which are mounted a plurality of rollers 41 upon which the billet travels downwardly of the chute. The chute 20 is supported at an inclination by means of a wheel-mounted stand 42 secured thereto and is provided at its upper end with an angularly disposed portion 43. The billet chute is placed in position with the upper 25 end of frame 40 adjacent opening 6 so that billets discharged through this opening on the chute 7 will be deflected by the angularly disposed portion 43 onto the rollers 41 and will travel downwardly thereof so as to 30 be discharged at a point convenient to the first rolls into which the billets are fed by an operator. The rollers 41 are of flanged construction, being provided at each end with a flange, as illustrated, and the frame 35 40 is of sufficient width to ensure that the billets will not slide off of the sides of the billet chute.

To ensure accuracy in operation of the furnace I provide means whereby the 40 return conveyor will be thrown out of operation as the receiving fork is tilted into position to place a pack upon one of the trays of the furnace conveyor, the return conveyor being thrown into operation again 45 as soon as the receiving fork is returned to receiving position. For this purpose the drive shaft 44 of return conveyor 33 is rotated by an electric motor 45 of suitable type supported upon a platform 46 secured on 50 top of one of the fire chambers 34. A suitable switch 46^a is connected into the circuit of this motor, the particular switch illustrated being a single throw single pole knife blade switch of known construction the blade 55 47 of which is connected by a link 48 to an arm 49 secured on shaft 10. When receiving fork 11 is turned into position to place a pack upon a tray of the furnace conveyor arm 49 is moved in such direction 60 as to move blade 47 into open position, as indicated in Fig. 14, breaking the circuit of motor 45 and stopping the return conveyor 33. Upon return of receiving fork 11 to receiving position blade 47 of the switch 65 is moved into operative position closing the

circuit of the motor and again throwing the return conveyor into operation so that another pack of sheets is discharged into the receiving fork and deposited thereby on a tray of the furnace conveyor. This operation is automatic and continuous during operation of the furnace and effectually eliminates all possibility of more than one pack of sheets at a time being fed into the receiving fork and possibly causing jamming 70 thereof resulting in throwing the furnace out of operation. In this respect the automatic control of the return conveyor for the packs of sheets is of importance as ensuring continuous and accurate operation of the 80 furnace so as to obtain maximum production and eliminate wasted time which is, of course, of prime importance in rolling operations.

The casing 1 is preferably provided with 85 suitable observation openings 1^a which are normally covered by suitable closure members or doors 50. In the modified form illustrated in Fig 10 a fire chamber 39^a is provided at each side of casing 1^b, this chamber 90 being provided with a bridge wall 51 in front of and adjacent grate 52. Beyond bridge wall 51 chamber 39^a is provided through its front wall and its back wall with an opening 53, these openings being disposed in alignment and of sufficient size to accommodate billets supported on rails 54 extending across chamber 39^a in advance of bridge wall 51. A suitable pusher 55 is slidably mounted in suitable supports 56 at the side of casing 1^b, 100 this pusher being provided with a head 57 for contact with billets to be pushed along the rails 54. In practice, billets to be heated are placed on the rails 54 at the lefthand end thereof as considered in Fig. 10 and are then pushed along these rails toward the other end thereof so as to be positioned in front of bridge wall 51, these billets being placed upon the rails so as to be heated during the completion of a run and while the 105 packs are passing through the furnace 1^b. After the run has been completed the billets which have been preheated are forced along the rails 54 so as to be discharged therefrom and are then fed onto the trays of the furnace conveyor at the front thereof, these billets being discharged from the conveyor in the manner previously described. This billet heating means is intended for use in connection with a short furnace, that is, a 110 furnace in which the casing 1^b is comparatively short so that the billets would not possibly be heated to a sufficiently high temperature during travel through the furnace without being first preheated to about the temperature desired. In using a long furnace such as that illustrated in the other figures of the drawings and previously described, this preheating of the billets is not necessary as the billets remain within the furnace casing 115 120 125 130

1 a sufficient length of time to be heated to the proper temperature before being discharged from the furnace. In all other respects, the construction and operation of the 5 modified form illustrated in Fig. 10 is identical with the furnace illustrated in the other figures of the drawings.

As will be understood, and as above indicated, changes in construction and arrangement of parts of the invention may be resorted to without departing from the field and scope of the same, and I intend to include all such variations, as fall within the scope of the appended claims, in this application in which the preferred forms only of my invention are disclosed.

What I claim is:—

1. In a furnace of the character described, an elongated casing inclined from one end 20 toward its other end, heat generating means at the lower end of the casing and communicating therewith, a conveyor traveling in the casing from the lower toward the upper end thereof, and means for receiving 25 articles discharged from said conveyor.

2. In a furnace of the character described, an elongated casing having its top wall inclined from one end, a fire chamber at the lower end of the casing and communicating 30 therewith, a stack communicating with the casing at the upper end thereof, and a conveyor traveling in the casing from the fire chamber toward said stack.

3. In a furnace of the character described, 35 an elongated casing having its top wall inclined from one end, heat generating means at one end of the casing and communicating therewith, and means for supporting and guiding the upper run of the conveyor, 40 said supporting means dividing the interior of the casing into an upper compartment and a lower compartment extending approximately the full length of the casing, said compartments communicating with 45 each other.

4. In a furnace of the character described, an elongated casing having its top wall inclined from one end, an endless conveyor operating within the casing lengthwise 50 thereof, means for supporting the upper run of the conveyor, said means dividing the interior of the casing into an upper compartment and a lower compartment communicating with each other, and heat 55 generating means at the lower end of the casing and communicating with the upper compartment thereof.

5. In a furnace of the character described, 60 an elongated casing having its top wall inclined from one end, an endless conveyor operating within the casing lengthwise thereof, means for supporting the upper run of the conveyor, said means dividing the interior of the casing into an upper compartment 65 and a lower compartment communica-

cating with each other, said supporting means being inclined upwardly toward the higher end of the casing, and heat generating means at the lower end of the casing and communicating with the upper compartment thereof.

6. In a furnace of the character described, an elongated casing having its top wall inclined from one end, an endless conveyor operating within the casing lengthwise 75 thereof, means for supporting the upper run of the conveyor, said means dividing the interior of the casing into an upper compartment and a lower compartment communicating with each other, said supporting means being inclined upwardly toward the higher end of the casing, a fire chamber at the lower end of the casing and communicating with the upper compartment thereof, and a stack communicating with the upper 80 end of the casing through the top wall thereof.

7. In a furnace of the character described, an elongated casing having its top wall inclined from one end, an endless conveyor 90 operating within the casing lengthwise thereof, means for supporting the upper run of the conveyor, said means dividing the interior of the casing into an upper compartment and a lower compartment communicating with each other, said supporting means being inclined upwardly toward the higher end of the casing, fire chambers at opposite sides of the lower end of the casing and communicating with the upper compartment thereof, and a stack communicating with the upper end of the casing through the top wall thereof.

8. In a furnace of the character described, an elongated casing having its top wall inclined from one end, an endless conveyor operating within the casing and having its upper run disposed substantially parallel with and adjacent the top wall of said casing, the upper run of the conveyor traveling toward the higher end of the casing, heat generating means communicating with the casing adjacent the lower end of the top wall thereof, and means for establishing communication between the interior of the casing adjacent the other end thereof and the atmosphere.

9. In a furnace of the character described, an elongated casing having its top wall inclined from one end, an endless conveyor operating within the casing and having its upper run disposed substantially parallel with and adjacent the top wall of said casing, the upper run of the conveyor traveling toward the higher end of the casing, heat generating means communicating with the casing adjacent the lower end of the top wall thereof and above the conveyor, and means for establishing communication between the interior of the casing adjacent 120

the other end thereof and the atmosphere.

10. In a furnace of the character described, an elongated casing having its top wall inclined from one end, an endless conveyor operating within the casing and having its upper run disposed substantially parallel with and adjacent the top wall of said casing, the upper run of the conveyor traveling toward the higher end of the casing,

10 heat generating means communicating with

the casing adjacent the lower end of the top wall thereof and above the conveyor, a stack communicating with the casing adjacent the higher end thereof and above the conveyor, and a baffle extending across the casing from 15 the top wall thereof and positioned adjacent and beyond the stack.

In testimony whereof I affix my signature.

JOHN J. JONES.
